(57) **CLAIM**

The ornamental design for a wireless modem, as shown and described.

DESCRIPTION

FIG. 1 is a right side elevational view of the wireless modem of our new design in a closed configuration, the left side elevational view being a mirror image thereof;

FIG. 2 is a front elevational view of the wireless modem shown in FIG. 1;

FIG. 3 is a rear elevational view of the wireless modem shown in FIG. 1;

FIG. 4 is a top plan view of the wireless modem shown in FIG. 1;

FIG. 5 is a bottom plan view of the wireless modem shown in FIG. 1;

FIG. 6 is a front perspective view of the wireless modem in FIG. 1;

FIG. 7 is a rear perspective view of the wireless modem shown in FIG. 1;

FIG. 8 is a right side elevational view of the wireless modem of our new design in an open configuration, the left side elevational view being a mirror image thereof;

FIG. 9 is a front elevational view of the wireless modem shown in FIG. 8;

FIG. 10 is a rear elevational view of the wireless modem shown in FIG. 8;

FIG. 11 is a top plan view of the wireless modem shown in FIG. 8;

FIG. 12 is a bottom plan view of the wireless modem shown in FIG. 8;

FIG. 13 is a front perspective view of the wireless modem shown in FIG. 8; and,

FIG. 14 is a rear perspective view of the wireless modem shown in FIG. 8.
